(57) **CLAIM**

The ornamental design for a security cable, as shown and described.

DESCRIPTION

FIG. 1 is a perspective view of a first embodiment of security cable showing my new design;

FIG. 2 is a front elevation view of the first embodiment;

FIG. 3 is a top plan view of the first embodiment;

FIG. 4 is a left side elevation view of the first embodiment;

FIG. 5 is a right side elevation view of the first embodiment;

FIG. 6 is a perspective view of a second embodiment of a security cable;

FIG. 7 is a front elevation view of the second embodiment;

FIG. 8 is a top plan view of the second embodiment;

FIG. 9 is a left side elevation view of the second embodiment;

FIG. 10 is a right side elevation view of the second embodiment;

FIG. 11 is a perspective view of a third embodiment of a security cable;

FIG. 12 is a front elevation view of the third embodiment;

FIG. 13 is a top plan view of the third embodiment;

FIG. 14 is a left side elevation view of the third embodiment;

FIG. 15 is a right side elevation view of the third embodiment;

FIG. 16 is a perspective view of a fourth embodiment of a security cable;

FIG. 17 is a front elevation view of the fourth embodiment;

FIG. 18 is a top plan view of the fourth embodiment;

FIG. 19 is a left side elevation view of the fourth embodiment;

FIG. 20 is a right side elevation view of the fourth embodiment;

FIG. 21 is a perspective view of a fifth embodiment of a security cable;

FIG. 22 is a front elevation view of the fifth embodiment;

FIG. 23 is a top plan view of the fifth embodiment;

FIG. 24 is a left side elevation view of the fifth embodiment;

and,

FIG. 25 is a right side elevation view of the fifth embodiment.

(Continued)

The break lines in the drawing indicate undermined length of the cable and the portion between these break lines form no part of the claimed design.
